WEB FEEDING APPARATUS FOR COLLATING MACHINES

Robert W. Ritzert, New York, N. Y., assignor to
 The Egry Register Company, Dayton, Ohio, a
 corporation of Ohio

Application May 9, 1945, Serial No. 592,834

8 Claims. (Cl. 270—52)

1

This invention relates to collating machines, and particularly to a mechanism for moving collated webs in predetermined increments and cause severance of the collated webs at predetermined intervals whereby to produce multiple copy form sets.

An object of the invention is to provide a machine for collating a plurality of continuous paper webs in such a manner that a carbon paper web is positioned between copy paper webs and are subsequently glued together so as to produce a multiple copy form set for simultaneously producing multiple copies of inscribed information.

Another object of the invention is to provide an improved feeding mechanism for advancing the copy and carbon paper webs intermittently in determined increments equal to the form length desired for aligning the various form faces on the multiple webs while causing adherence between the copy and carbon paper webs, and to subsequently sever the webs in predetermined lengths for providing individual multiple copy form sets.

Still another object of the invention is to provide an improved feeding mechanism for feeding and aligning a plurality of paper webs by mechanical means which engages the webs and advances them a predetermined distance as controlled by a mechanical stop which prevents overfeeding of the webs at each feeding cycle of the machine.

Another object of the invention is to provide an improved feeding mechanism for a plurality of paper webs wherein they are moved by means of an intermittently operated chain which is accurately controlled as to the length of each movement of the chain by means of a releasable mechanical stop which prevents any overfeeding of the webs by the intermittently moving chain.

Another object of the invention is to provide an improved driving mechanism for the feeding mechanism of a collating machine wherein the means which removes the webs from the supply rolls can be driven at any desired speed and the speed thereof be readily changeable so as to maintain a satisfactory slack looped condition between the means which withdraws the webs from the supply rolls and the feeding and gluing mechanism of the collating machine.

Still another object of the invention is to provide means for readily adjusting the individual tension applied upon each of the webs passing through the collating machine so that all of the webs can be maintained under substantially the same tension when passing through the feeding

2

mechanism so as to permit proper accurate alignment of the form faces on the co-operating webs.

Another object of the invention is to provide a feeding mechanism for a paper web to advance the same in predetermined increments of length wherein a positive lock is provided to prevent overthrow of the feeding mechanism at the end of the feeding stroke thereof, and which locking mechanism is readily tripped to permit a subsequent feeding operation to occur.

Still another object of the invention is to provide an improved stacking mechanism for receiving lengths of the paper web as severed from the continuous length thereof during operation 15 of the collating machine so as to arrange the sheets in aligned stacks.

Still another object of the invention is to provide a collating machine, or web feeding apparatus, constructed in accordance with any of the foregoing objects, wherein a paper web fed through the machine is severed longitudinally in order to provide two separate forms from a single continuous web, and wherein the gluing mechanism of the machine is arranged so as to cause adherence between the adjacent webs passing through the machine in a manner that the severance of the web can occur between parallel glue lines whereby the pairs of webs formed by the severance will be secured together by glue lines running along one edge thereof.

Still another object of the invention is to provide an intermittently advancing chain drive for feeding a paper web through a machine in predetermined increments, and to provide latch means for positively stopping the chain in a predetermined position during each intermittent advancing movement, which latching means can be readily tripped upon release thereof and initiation of a subsequent advancing movement of the feed chain.

Still another object of the invention is to provide a collating machine wherein a plurality of paper webs pass through a gluing station, through an aligning and feeding mechanism, and thence 45 through a severing device for passage into a stacking mechanism, the stacking mechanism being driven by and synchronized with the operation of the gluing mechanism whereby the stacking mechanism operates when the gluing and feeding mechanisms are idle.

Further objects and advantages will become apparent from the drawings and the following description.

Figure 22 is a plan view of the collated paper webs passing through the machine illustrated in

Figure 1 with certain portions thereof broken away to illustrate the manner in which the webs are glued together in order to produce two parallel arranged sets of multiple copy form sheets for subsequent severance longitudinally along the web in the manner illustrated in Figure 21.

Figure 23 is an elevational view of the slitting mechanism illustrated in Figure 21.

Figure 24 is a partial cross-sectional view illustrating the brake mechanism for the driving motor.

Figure 25 is a cross-sectional view taken substantially along line 25—25 of Figure 24.

This invention consists of a feeding mechanism 15 for removing webs of paper and carbon from supply rolls, a gluing mechanism 15 through which the paper webs are fed to receive adhesive thereon and an aligning and intermittent feeding mechanism 20 that aligns the collated webs and feeds them in predetermined increments of length, determined by the size of the form to be produced, to a severing mechanism 25 which is intermittently operated to sever the collated webs in predetermined lengths.

The collating machine of this invention is adapted to produce a multiple copy form such as that illustrated in Figure 11 wherein a plurality of copy or paper sheets 11, 12 and 13 have carbon sheets 14 and 16 interleaved therebetween so as to simultaneously produce a plurality of carbon copies of data placed upon the top or face sheet 11. The paper webs 11 and 12 are each provided with a pair of parallel lines of adhesive 17 and 18 on one face thereof, and specifically on the underside of the respective sheets as illustrated by the turned down upper right-hand corner of the sheet 11 in Figure 11. The upper line of adhesive 17 is provided for securing adjacent copy or paper webs together along one edge thereof while the adhesive line 18 is provided for securing the carbon sheets 14 and 16 to the underside of the paper webs 11 and 12, respectively. The paper sheets 11, 12 and 13 are each provided with a perforation line 19 upon which the forms are severed or torn so that the individual sheets 11, 12 and 13 can be removed from the stub end 21 of the form to which the carbon sheets 14 and 16 will be secured.

One or more holes 22 are provided between the lines of adhesive 17 and 18 for use as file holes, which are also used to provide alignment between the paper webs when they are being collated in the collating machine.

In this invention the paper webs and the carbon paper webs are provided in the form of rolls 23 and 24, respectively, that are supported upon a suitable frame structure 26. A sufficient number of rolls of paper or copy webs and carbon paper webs are provided for supplying the collating machine according to the number of copy sheets that are to be provided in the multiple copy form. The paper webs 23a and the carbon paper webs 24a are supplied alternately to the feeding mechanism 10 to thereby collate and interleave the carbon paper webs between copy paper webs.

Each of the webs 23a and 24a pass between a pair of feeding rolls 27 and 28, more particularly shown in Figure 6. The feed roll 28 is drivably connected to a drive shaft 29 by means of a pair of bevel gears whereby the roll 28 is positively driven, see Figure 1. The roll 27 is carried upon a frame 31 that is supported upon a pivot shaft 32 supported in the frame structure 33 of the feeding mechanism 10. The frame 31

is urged in a downward direction, see Figure 6, by means of a compression spring 34 retained between a stationary bracket 35 secured to the frame structure 33 and a nut 36 carried upon a pin 37 secured to the frame 31. The paper or carbon web, as the case may be, is thus frictionally driven by the roll 28, the roll 27 retaining sufficient compression upon the web for such a friction drive.

A rotatable shaft 38 having an eccentric portion 39 thereon engages the frame 31 to lift the same from the roll 28 for threading the paper or carbon webs between the rolls 27 and 28. A paper bale 40 extends from the frame 31 to permit the paper and carbon webs to fall vertically in front of the frame structure 33 without interference with one another.

The drive shaft 29 of the feeding mechanism 10 is driven by the shaft 41 through a pair of bevel gears 42, the shaft 41 being driven by the driving mechanism of the feeding and aligning mechanism 20 in a manner which will be hereinafter described.

From the feeding mechanism 10 is alternately positioned paper copy webs 23a and carbon paper webs 24a which pass into the gluing mechanism 15, more specifically illustrated in Figures 10, 12 and 13.

The gluing mechanism consists of a main frame structure 42 having a plurality of rods 43 extending transversely across the same in parallel arrangement that provides a supporting means for glue pots 44 positioned thereupon. The glue pots are adjustably positioned on the rods 43 to dispose them at any location transversely of the frame structure 42 and thus cause application of glue lines at any position transversely of the paper webs passing thereover. A plurality of guide rolls or rods 45 are also positioned transversely across the frame structure 42 of the gluing mechanism 15 for guiding the direction of movement of the paper and carbon webs 23a and 24a through the machine.

An auxiliary frame structure 46 is carried above the main structure 42 of the gluing mechanism and is movably carried thereon by means of the hinge links 47, whereby the auxiliary frame structure 46 may be raised into the position illustrated in Figure 13 when threading the paper and carbon webs through the gluing mechanism 15 or when the machine is shut down over night to prevent the paper webs adhering to the glue rolls in the glue pots 44. The auxiliary frame structure 46 is provided with a plurality of guide rolls or rods 48 that extend transversely across the same for guiding the paper and carbon webs in a collated condition to the aligning and intermittent feeding mechanism 20 hereinafter described. The auxiliary frame 46 also carries a plurality of rolls or rods 49 that engage the paper webs 23a to retain the same in engagement with the glue wheels located in the glue pots 44.

The glue wheels 50, more specifically shown in Figure 10, consist of thin disc members that are mounted in the glue pots 44 upon a drive shaft 51. The drive shaft 51 is driven by a pair of bevel gears 52 from a common power shaft 53 that in turn is driven by a pair of bevel gears 54 through a drive shaft 55. The drive shaft 55 is drivingly connected to a sprocket chain 56 through a ratchet mechanism 57 for driving the shaft 55 when the chain 56 moves in one direction only in a manner to be hereinafter described in connection with the driving mechanism for

the aligning and feeding mechanism 20. The glue wheels 50 are each adapted to provide one line of adhesive on the paper webs 23a so that the lines of adhesive 17 and 18 will be applied along the edge of the paper webs as they pass through the machine.

Tension control devices 60, more specifically shown in Figures 13, 14, 15 and 16, are provided for regulating the tension on the paper and carbon webs 23a and 24a when passing through the gluing mechanism 15 so that there will be a substantially uniform tension on all of the webs passing from the gluing mechanism 15 into the feeding and aligning mechanism 20 for thereby aiding alignment of the webs and preventing any tendency of buckling of the webs when passing through the aligning mechanism 20.

These tension control devices each consist of a rod 61 that passes transversely across the gluing mechanism 15 and is supported in a frame member 62 provided on each side of the gluing mechanism 15, the frame member 62 being in turn supported by the downwardly extending portions 63 on the frame member 42. The rods 61 are provided with aligning collars 64 between which the paper webs pass for retaining the paper and carbon webs in proper transverse alignment when passing through the gluing mechanism 15 and thus maintain them in alignment when entering the aligning mechanism 20. The collars 64 are adjustable on the rods 60 for independently transversely positioning the webs in the gluing mechanism to thus individually position each of the webs in a predetermined transverse position with respect to the remaining webs so that the carbon webs can be positioned inwardly of the ends of the paper webs whereby to produce the arrangement of form illustrated in Figure 11.

The tension control devices 60 further consist of a wire bale 65 that is secured at one end thereof to a control arm 66 pivotally mounted upon the rod 61. The control arm 66 is provided with a tightening screw 67 receiving the thumb nut 68 for securing the arm 66 in any desired position, the tightening screw 67 extending through an arcuate slot 69 provided in the frame member 62 whereby rotation of the arm 66 about the pivot shaft 61 will cause the wire bale 65 to move around the pivot shaft 61 to change the tension loop 70, see Figure 12, of the paper and carbon web for regulating the degree of tension thereon.

The rods 61 are of themselves adjustably transversely of the gluing mechanism 15 to provide small and accurate transverse adjustment of the collars 64 to accurately position the paper webs in proper vertical register. The rods 61 have a threaded end 71 threadedly received by the frame member 42, see Figure 15, whereby rotation of the rod 61 will cause the same to move transversely of the gluing mechanism. A locking collar 72 is provided on the opposite threaded end 73 of the rod 61 for locking the same in position.

The aligning and intermittently feeding mechanism 20, which also incorporates the driving mechanism for the machine, consists of a frame structure 74 having a table top 75 over which the collated paper webs 23 and carbon webs 24a pass when being fed by the feeding mechanism 20.

The power mechanism, or driving mechanism, consists of an electric motor 76, preferably of the variable speed type, suitably mounted upon the frame structure 74, see Figures 1, 2 and 7. A pulley 77 is secured to the shaft of the motor 76 and drives a pulley 78 mounted upon the drive

shaft 79 which carries a pinion gear 80 for driving the spur gear 81 secured to the power shaft 82. The power shaft 82 carries a crank arm 83 to which a connecting rod 84 is suitably attached having one end thereof carried by the crank pin 85 that is adjustably positioned in the crank 83 by means of the adjusting block 86 and the adjusting screw 87 whereby the stroke of the crank pin 85 relative to the power shaft 82 is regulated. The opposite end of the connecting rod 84 is connected to an oscillating arm 88 by means of a pin 89, the oscillating arm 88 being pivotally secured to the frame 74 by means of the bearing pin 90, see Figure 1. The upper end of the oscillating arm 88 carries the driving mechanism 91, to be hereinafter described, for driving the feed chain 92 intermittently for intermittently moving the collated webs passing across the table 75.

The power or driving mechanism is provided with a braking device that is adapted to quickly stop the operation of the driving mechanism in case of difficulty with the paper webs passing through the machine, such as brakage or other conditions. The driving motor 76 is provided with a brake wheel 200, see Figs. 24 and 25, that is mounted upon the drive shaft of the electric motor 76. The brake wheel 200 is adapted to be engaged by a brake member 201 that is carried upon one end of a brake lever 202 that is pivotally mounted upon the bracket 203 secured to the frame of the machine by means of the pin 204. The brake lever 202 carries a switch 205 that is of the mercury type for controlling operation of the electric motor 76.

The brake lever 202 carries a bracket 206 that is provided with a latch member 207 extending transversely thereof. A compression spring 208 engages the head 209 of the latch member 207 for normally urging it in a rightward direction as viewed in Figure 25 to thereby extend the head 209 of the latch member 207 beyond the side wall of the bracket 206. The opposite end of the latch member 207 carries a pin 210 that is engaged by one end of a bell-crank lever 211 that is pivotally mounted upon the pin 212 carried in a bracket 213 secured to the brake lever 202 by means of the arm 214.

The brake lever 202 is provided with a foot pedal portion 215 adapted to be engaged by the operator's foot to depress the same and thereby cause the brake member 201 to engage the brake wheel 200 to stop the motor 76 whenever trouble occurs on the machine, the mercury switch 205 at that time opening the power lines 216.

When the brake lever 202 is pressed downwardly, as viewed in Figure 24, the latch member 209 is adapted to engage a latch strike 220 to thereby hold the lever 202 in a downward position with the brake member 201 against the brake wheel 200, the latch head 209 passing under the strike 220 and being retained by the ledge 221.

When the machine is to be started after operation of the brake mechanism, the bell-crank lever 211 is operated to rotate in a counter-clockwise direction, as viewed in Figure 25, to remove the latch head 209 from beneath the strike 220 and thereby permit the spring 222 to pull the brake lever 202 upwardly and release the brake 201 from the brake wheel 200.

The power shaft 82 carries a pulley 93 that is drivingly connected with the pulley 94 by means of the belt 95, the pulley 94 providing the drive connection for a variable speed drive pulley 96 that is connected through a belt 97 with the power pulley 98 which drives the shaft 41 heretofore 75

referred to through means of the bevel gears 99 whereby the speed of feeding movement of the paper webs 23a and the carbon webs 24a can be controlled through the feeding rolls 27 and 28 and thereby regulate the length of the slack loops 100 provided between the feeding device 10 and the gluing mechanism 15. The drive pulley 96 is more specifically shown in cross section in Figure 8 wherein the pulley is shown as being constructed in two parts 96a and 96b, the part 96b being secured to the power shaft 101, and the part 96a being keyed to the shaft 101 by means of the key 102 but slidably axially thereon. A compression spring 103 engages the hub of the pulley part 96a for constantly urging the same toward the pulley part 96b tending to cause the belt 97 to ride toward the outside of the groove formed by the pulley parts.

The variable speed power pulley 96 is carried upon an arm member 104 that can oscillate about a stationary pivot bearing 105 carried on the frame member 106 of the frame structure 74. The arm 104 carries the bearing member 107 for the shaft 101 whereby oscillation of the arm 104 about the pivot bearing 105 causes the pulley 96 to be moved away from or toward the pulley 98 and thereby causing the belt 97 to ride between the pulley parts 96a and 96b at different radii to change the driving speed of the pulley 98 and thus change the driving speed of the feed rolls 28 of the feeding mechanism 10 to regulate the slack loop length 100.

To adjust the tension on the belt 108 between the driving pulleys 93 and 94, see Figure 7, the pulley shaft 101, see Figure 8, is carried in an eccentric bearing member 109 that is positioned in the bearing support member 107 whereby rotation of the eccentric bearing member 109 will cause an increase or decrease in the axial distance between the pulleys 93 and 94, whereby the tension on the belt 108 can be adjusted. A set screw 110 is provided in the bearing block 107 to secure the eccentric bearing member in a position after proper adjustment has been made.

To regulate the speed of the drive pulley 98, as hereinbefore referred to, the arm 104 is oscillated about the pivot bearing 105 by means of a threaded rod 111, see Figures 1 and 2, that threadedly receives a block 112 having a pin 113 therein engaging the slot 114 in the arm 104, whereby rotation of the shaft 111 axially moves the block 112 to cause the pin 113 to move the arm 104. A suitable manual control 115 is provided for rotating the threaded rod 111.

The intermittent feeding and aligning mechanism for advancing the collated webs in predetermined increments of length consists of a sprocket chain 116, see Figures 2, 3 and 4, that is supported by means of a plurality of sprocket wheels 117 to form a closed circuit with a portion of the sprocket chain 116 positioned adjacent the table 75. The sprocket chain 116 carries a plurality of pins 118 that engage the holes 22 provided in the paper webs along one edge thereof to thereby advance the collated paper webs through the machine. It will be understood from the foregoing description that the paper and carbon webs are collated by the feeding mechanism 10 and glue is applied to one side of certain of the paper webs when passing through the gluing mechanism 15 so that when the collated paper webs arrive at the aligning mechanism 20, the glue is still in a wet condition so that the pins 118 tend to align the adjacent paper webs by engagement with the holes 22, and prevent the col-

lated webs from slipping relatively to each other when being fed through the feeding mechanism in intermittent and predetermined advancing motions. The length of each advancing motion of the chain 116 determines the length of the collated paper webs that are advanced to the shearing device 25 and thereby controls the length or width of the multiple copy form set that is being produced.

Mechanism for regulating the intermittent advancement of the feed chain 116 is more specifically shown in Figures 3 and 4 wherein the oscillating arm 88, heretofore described, carries a pawl 119 pivotally mounted upon an arm 120 secured to the arm 88 by means of a pivot pin 121. The pawl 119 is provided with a tail 122 that engages a stop pin 123 that is also secured to the arm 120. A tension spring 124 is positioned between a pin 125 carried upon the pawl 119 and a stationary pin 126 secured to the arm 120 so that the pawl 119 normally tends to rotate in a counterclockwise direction, as viewed in Figure 3, to retain the tail 122 of the pawl 119 against the stop pin 123.

The nose of the pawl 119 is provided with an arcuate recess for engaging pins 128 secured to the sprocket chain 116 at regular spaced intervals.

It will thus be seen that when the arm 88 moves in a rightward direction as viewed in Figure 3, that the pawl 119 will engage a pin 128 on the sprocket chain 116 to cause the chain 128 and the chain connected thereto to move in a rightward direction. The length of the movement in a rightward direction of the arm 88 is controlled by the stroke of the crank pin 85 so that the pin 128 and the chain 116 will thus be moved in a rightward direction a predetermined distance.

It will be noted from Figure 2 that the pawl 119 operates on the lower half of the chain 116, which when moved in a rightward direction as just described, causes the upper half of the chain 116 to move in a leftward direction and thereby advance the collated paper webs toward the shearing mechanism 25 a predetermined distance.

Since the chain 116 travels at a relatively high rate of speed when paper is being fed thereby, it will be appreciated that the chain 116 would have a tendency to coast at the end of each intermittent motion thereof which would thereby prevent accurate predetermined movement of the collated paper webs and thus prevent severance of the webs at a predetermined location upon each advancing movement thereof.

To eliminate any overthrow condition of the chain 116, a releasable stop 130 is positioned adjacent the end of the stroke of the pawl 119. This releasable stop consists of an L-shaped lever pivoted upon a pin 131 that is secured to a bracket 132 slidably mounted upon the guide rails 133 to permit positioning of the releasable stop 130 at any position along the length of the machine. One end of the L-shaped lever is retained against a stop pin 134 secured to the bracket 132 by means of a tension spring 135 that extends between a pin 136 on the lever 131 and a stationary pin 137 on the bracket 132, thereby tending to rotate the releasable stop 130 in a counterclockwise direction to hold the same in position as shown in Figure 3.

It will thus be seen that the releasable stop 130 may be freely rotated in a clockwise direction, when the mechanism is as positioned in Figure 3, and that it will always be returned to

the position illustrated in Figure 3 by the spring 135.

However, when the chain 116 moves in a rightward direction carried by the pin 128 and the pin 128 reaches the end of its rightward stroke, as viewed in Figure 3, the stop 130 must not rotate in a clockwise direction. Thus, the pawl 119 is provided with an arcuate surface 138 along the lower edge thereof that rides upon the flat surface 139 of the stop 130 so that when the mechanism is in the position as illustrated in Figure 4, the pin 128 will be positively locked between the pawl 119 and the stop 130. As soon as the pawl 119 is retracted, or moved to the left, to start a new stroke and engages the next pin 128 in regular sequence, the pin 128 that has been moved against the stop 130 can rotate the same clockwise to permit free movement of the chain 116 in a rightward direction. It will be apparent that the pawl 119, being pivotally mounted for clockwise rotation will pass under the pins 128 when returning to its initial starting position upon each stroke of operation.

The collated paper webs are fed toward the severing or cutting device 25 which reciprocates once for each revolution of the crank pin 85 so that the movement of the cutting mechanism is synchronized with the operation of the feeding mechanism for the paper webs, the length of web fed by the feeding mechanism 20 determining the point at which the web will be severed. A suitable driving mechanism for the cutting mechanism 25 consists of a power shaft 140 driven by the power shaft 82 for rotating an eccentric 141 which reciprocates the knife head 142.

The glue wheels 50, previously mentioned, driven by the sprocket chain 56, see Figure 9, are rotated only when paper webs are moving through the machine. During the idle stroke of the paper feeding mechanism as controlled by the arm 88, the chain 56 is moved in a reverse direction to its feeding movement but the glue wheels are not rotated. For this purpose the ratchet mechanism 57 is adapted to drive the shaft 55 only when the lower half of the chain 56, as viewed in Figure 9, is moved in a rightward direction by the oscillating arm 144. The arm 144 is arranged parallel to the arm 88 and is oscillated therewith so that the chains 56 and 116 move simultaneously during the feeding stroke of the arm 88. During the retraction stroke the chain 116 is stationary but the chain 56 is moved in a reversed direction. The arm 144 has a slot 145 that engages a pin 146 on the chain 56 whereby it is reciprocated upon oscillation of the arm 144.

The sprocket shaft 147 is adapted to drive the sprocket chain 150 through a ratchet mechanism 151 whereby the chain 150 is driven only when the arm 144 is moving in a leftward direction, whereby the chain 150 is driven when the web feeding chain 116 is idle, whereby a stacking mechanism driven by the sprocket chain 150 will operate during the idle period of the feeding mechanism 20.

The stacking mechanism is illustrated in Figures 17, 18 and 19 wherein the power sprocket chain 150 drives a sprocket wheel 152 for driving the sprocket chain 153. The sprocket chain 153 carries a plurality of paper gripping members 154 that are adapted to receive the forward edge of the paper web passing from the feeding mechanism 20 and to remove the same into a stack after the knife 25a of the cutting device has severed a length of the web therefrom. The sprocket wheels 152 and 155 of the stacking mechanism

are carried upon a frame structure 156 pivoted about the drive shaft 149 for the sprocket wheel 152. The sprocket chain 153 extends over a receiving box 157 that has a movable platform or floor 158 that moves downwardly as form sets are introduced into the receiving box.

The floor 158 of the receiving box 157 is adapted to be carried between a pair of sprocket chains 159, each of which is positioned on opposite sides of the floor 158, suitable hooks or pins being provided to carry the floor 158 on the sprocket chains 159. The sprocket chain 159 is driven by a sprocket wheel 160 that is in turn driven by a shaft 161 co-operating with a worm 162 and a worm wheel 163 that are driven by a sprocket chain 164 that is in turn driven by a suitable sprocket carried upon the drive shaft 149. The floor 158 is thus gradually lowered through the driving mechanism just described when the chain 153 is driven in a manner heretofore described. The paper gripping members 154, see Figure 20, are suitably carried upon one of the links of the sprocket chain 153 and are provided with a leaf spring finger adapted to engage a stationary finger 166 to bind a paper sheet between the fingers. A cam member 167 carried upon the shaft 168 is positioned adjacent each of the drive chains 153 so that when the paper gripping members 154 are positioned as shown in Figure 17, the pin 169 will engage the cam 167 to cause the finger 165 to move out of engagement with the fingers 166.

As previously stated the stacking mechanism operates when the paper web in the aligning mechanism is stationary and vice versa. As illustrated in Figure 17 the stacking mechanism is in the position which occurs just after the collated paper web has been advanced a predetermined increment of length and the severing mechanism 25 has operated the knife 25a to sever a length of web from the continuous web. The paper feeding mechanism is then ready to move on a retraction stroke which will result in operation of the stacking mechanism through operation of the arm 144 in the manner heretofore referred to so that the severed length of web 170 will be advanced by the stacking mechanism to deposit the same in the receiving box 157. The pin 169 of the paper gripping mechanism 154 permits the finger 165 to clamp upon the severed length of web 170 as soon as the stacking mechanism begins movement. The severed length of web 170 will strike the rear wall 171 of the receiving box 157 and be withdrawn from the paper gripping device 154 and will fall by gravity upon the floor 158. By the end of the retraction stroke of the arms 28 and 144 another gripping member will be in the position illustrated in Figure 17 ready to receive another severed paper web when it is advanced by the feeding mechanism 20.

In order to prevent the paper webs from lifting from the table 75 when the pins 118 on the chains 116 are brought into engagement with the holes 22 in the paper webs, guide brackets or plates 172 are positioned above the table 75. These guide plates 172 are positioned in spaced parallel arrangement so that the pins 118 can pass freely therebetween and are spaced upwardly from the table 75 to permit the collated paper webs to pass beneath the same and yet retain them in engagement with the pins 118. The guide plates 172 may be adjustably mounted on the table 75 by means of the brackets 173.

A stripper plate 174 is provided at one end of the table 75, as illustrated in Figure 2, to lift the collated paper webs from the pins 118 before they

pass around the end sprocket wheel 117 to thereby prevent the pins from tearing the holes 22 in the paper webs.

In Figure 14 there is illustrated a driving arrangement for the rolls or rods 45 and 48 of the gluing mechanism previously referred to in Figure 12. In some instances it may be necessary to drive these rolls in order to make the machine run as lightly and freely as possible. In this instance the outer ends of the rolls 48 and 45 are provided with sprocket wheels 175 and 176 that are driven by the sprocket chains 177 and 178, respectively, a sprocket chain 179 interconnecting the sprocket drive from the sprockets 176 to the sprockets 175, a power chain 180 being provided for supplying power to the sprockets 176.

The apparatus as hereinbefore described has been described principally in production of a multiple copy form of the type illustrated in Figure 11. In this type of form the width of the continuous web controls the length of the form and the length of the continuous web fed by the feeding mechanism 20 controls the width of the form. In Figure 22 there is illustrated a continuous paper web, or rather a collated web of a type that is adapted to be split longitudinally along the center line, such as along the dot dash line 181 whereby two forms of the type illustrated in Figure 11 can be produced simultaneously. In the arrangement illustrated in Figure 22, four glue lines 182, 183, 184 and 185 will be applied upon the paper webs in the manner heretofore described and positioned longitudinally along the center of the web as illustrated in Figure 22. Two carbon paper webs will be placed side by side and extend in parallel arrangement longitudinally of the paper webs so that each carbon web will be secured by an individual glue line 182 or 185. The paper webs will be secured together by the two glue lines 183 and 184. Thus, when the collated web is severed along the dot dash line 181 two forms of the type illustrated in Figure 11 will be produced. The slitting mechanism 190 may be positioned just ahead of the severing or cutting device 25 so that a slit 186 will be produced in the collated web just before it is severed. The slitting mechanism 190 may consist of a pair of rotating slitting wheels 187 and 188 supported upon the shafts 189 and 191, respectively. The slitting wheel 187 is driven by a sprocket chain 192 through a shaft 193, a chain 194, a shaft 195 and a pair of spur gears 196, while the wheel 188 is driven by the sprocket chain 192, the shaft 193, the chain 197, the shaft 198 and the chain 199. The slitting mechanism 190 has the slitting wheels 188 and 187 extending through the table 75 and may be rotated at any desired speed from any of the rotating drive members of the collating machine.

While the apparatus disclosed and described herein constitutes a preferred form of the invention, yet it will be understood that the apparatus is capable of mechanical alteration without departing from the spirit of the invention, and that all such modifications as fall within the scope of the appended claims are intended to be included herein.

Having thus fully described my invention what I claim as new and desire to secure by Letters Patent is:

1. A collating machine comprising, means for withdrawing a plurality of paper webs from supply rolls and for advancing the same toward an adhesive applying mechanism, an adhesive applying mechanism for receiving the paper webs

and applying adhesive to at least some of them whereby to cause adherence between the webs, and a feeding and aligning mechanism for intermittently moving determined lengths of the webs toward a shearing device, said feeding and aligning mechanism including a flexible belt having means for engaging the paper webs to advance the same upon movement of the belt, reciprocating means for intermittently moving said belt in determined increments of movement, and stop means engaged by said reciprocating means at the end of each determined movement thereof for feeding the paper webs whereby to temporarily lock said belt against movement in either direction and thereby accurately position the belt at the end of each feeding stroke of the reciprocating means.

2. A collating machine comprising, means for withdrawing a plurality of paper webs from supply rolls and for advancing the same toward an adhesive applying mechanism, an adhesive applying mechanism for receiving the paper webs and applying adhesive to at least some of them whereby to cause adherence between the webs, and a feeding and aligning mechanism for intermittently moving determined lengths of the webs toward a shearing device, said feeding and aligning mechanism including a flexible belt having means for engaging the paper webs to advance the same upon movement of the belt, reciprocating means for moving said belt in determined increments of movement and including a latch member for drivingly engaging said belt in one direction only of said reciprocating means, and releasable stop means engaged by said latch member at the end of the web feeding stroke thereof to temporarily lock the belt against movement in either direction and thereby accurately control the stopping position of the belt upon each movement thereof.

3. A collating machine comprising, means for withdrawing a plurality of paper webs from supply rolls and for advancing the same toward an adhesive applying mechanism, an adhesive applying mechanism for receiving the paper webs and applying adhesive to at least some of them whereby to cause adherence between the webs, and a feeding and aligning mechanism for intermittently moving determined lengths of the webs toward a shearing device, said feeding and aligning mechanism including a flexible belt having means for engaging the paper webs to advance the same upon movement of the belt, driving means movable longitudinally of said belt in a reciprocating motion for moving said belt in one direction only and including latch means for engaging pin means extending from said belt whereby to drive said belt therethrough, and releasable stop means engaged by said latch means at the end of the web feeding stroke thereof to temporarily lock said pin means between said latch means and said stop to thereby positively locate said pin means in a determined position at the end of each web feeding stroke.

4. A collating machine comprising, means for withdrawing a plurality of paper webs from supply rolls and for advancing the same toward an adhesive applying mechanism, an adhesive applying mechanism for receiving the paper webs and applying adhesive to at least some of them whereby to cause adherence between the webs, and a feeding and aligning mechanism for intermittently moving determined lengths of the webs toward a shearing device, said feeding and aligning mechanism including a flexible belt

having means for engaging the paper webs to advance the same upon movement of the belt, driving means movable longitudinally of said belt in a reciprocating motion for moving said belt in one direction only and including latch means for engaging pin means extending from said belt whereby to drive said belt therethrough, and releasable stop means spring actuated to position the same to stop movement of said pin means upon engagement thereof by said latch means whereby to lock said pin means between the stop means and said latch means, said stop means being movable by said pin means when said latch means is out of engagement thereof to permit a subsequent web feeding stroke of said belt by said latch means.

5. A feeding mechanism for a paper web that includes the combination of, a flexible belt having means for engaging a paper web to advance the same, pin means extending from the belt for engagement by driving means whereby to move the belt, driving means movable longitudinally of the belt in a reciprocating motion for driving the same and including latch means for engaging said pin means in one direction of movement only of said driving means whereby said belt is moved in one direction only by the reciprocating motion of the driving means, and releasable stop means engaged by the pin means as moved thereagainst by the latch means at the end of the longitudinal movement thereof as caused by the driving means whereby to temporarily lock said pin means between said stop means and said latch means and thereby prevent movement of said belt in either direction at the end of the web feeding stroke thereof.

6. A feeding mechanism for a paper web that includes the combination of, a flexible belt having means for engaging a paper web to advance the same, pin means extending from the belt for engagement by driving means whereby to move the belt, driving means movable longitudinally of the belt in a reciprocating motion for driving the same and including latch means for engaging said pin means in one direction of movement only of said driving means whereby said belt is moved in one direction only by the reciprocating motion of the driving means, and releasable stop means spring actuated to position the same for engagement by said pin means when moved thereagainst by said latch means, said stop means including means engaged by said latch means when said pin means engages said stop means to prevent movement of said stop means and thereby lock said pin means between said stop means and said latch means.

7. A collating machine comprising, a feeding mechanism for withdrawing paper webs from supply rolls, a feeding and aligning mechanism for intermittently moving the paper webs toward a shearing device, and a driving mechanism for the aforesaid mechanisms consisting of crank means drivingly connected to a power source and operated thereby, an oscillating arm drivingly connected to said feeding and aligning mechanism, a connecting rod interconnecting said oscillating arm and said crank arm for thereby moving said oscillating arm in direct proportion to the eccentric stroke of said crank arm, a changeable speed pulley carried upon an oscillatable arm, means drivingly connecting said pulley with said power source, belt means drivingly connecting said pulley to said feeding mechanism for withdrawing paper webs from the supply rolls, and means for oscillating said last

mentioned arm whereby to change the effective pulley diameter of said changeable speed pulley upon the belt means moving thereover for changing the speed of operation of said web with-drawing feeding means.

8. A feeding mechanism for a paper web that includes the combination of, a flexible belt having means for engaging a paper web to advance the same, means extending from the belt for engagement by driving means whereby to move the belt, driving means movable longitudinally of the belt in a reciprocating motion for driving the same and including latch means for engaging said first named means in one direction of movement only of said driving means whereby said belt is moved in one direction only by the reciprocating motion of the driving means, and releasable stop means engaged by the first named means as moved thereagainst by the latch means at the end of the longitudinal movement thereof as caused by the driving means whereby to temporarily lock said first named means between said stop means and said latch means and thereby prevent movement of said belt in

either direction at the end of the web feeding stroke thereof.

ROBERT W. RITZERT.
